UNITED STATES PATENT OFFICE.

JOHN M. TORMEY, OF CENTRAL FALLS, RHODE ISLAND.

CENTER-GAGE.

1,096,769.

Specification of Letters Patent. Patented May 12, 1914.

Application filed December 10, 1912. Serial No. 736,018.

To all whom it may concern:

Be it known that I, JOHN M. TORMEY, a citizen of the United States, residing at Central Falls, in the county of Providence and State of Rhode Island, have invented 5 new and useful Improvements in Center-Gages, of which the following is a specification.

This invention relates to improvements in 10 center gages and has particular application to a device of the class described which may be used as a center punch and scribe.

In carrying out the present invention, it 15 is my purpose to provide a center gage or punch whereby the center of cylindrical, square, and rectangular objects may be accurately and quickly located and which, as in the case of rectangular objects, may be moved along such objects to scribe the center 20 line thereon.

It is also my purpose to provide a device 25 of the type set forth which will embrace the desired features of simplicity, efficiency, durability and strength and which when in use will function accurately.

With the above and other objects in view, 30 the invention consists in the construction, combination and arrangement of parts hereinafter set forth in and falling within the scope of the claim.

In the accompanying drawing; Figure 1 is a side elevation of a gage constructed in accordance with the present invention, the same being shown as applied to an object. 35 Fig. 2 is a transverse sectional view taken through the center of the gage. Fig. 3 is a bottom plan view of the gage parts being broken away.

Referring now to the accompanying drawing in detail, the numeral 1 indicates the 40 body of the gage or instrument, the said body being preferably composed of a rectangular bar of metal having the opposite side edges thereof provided with longitudinally 45 extending grooves 2, 2 and formed centrally with an aperture or opening in which is securely fastened a hollow shank 4 having loosely mounted thereon a pinion 5 having the teeth thereof disposed within the grooves 2, 2. Secured to the upper end 50 of the shank 4 is a boss 6 formed with a bore coaxial with the hollow shank 4 and through the bore in the boss 6 and the hollow shank is passed a punch 7.

Slidably disposed upon the body 1 at the 55 opposite sides of the boss 6 are jaws 8, 8

having the confronting faces thereof at the side of the body 1 opposite from that side carrying the boss 6 formed with V-shaped notches 9 merging into straight edges 10. 60 Suitably secured to each jaw 8 and disposed within the respective groove 2 is a rack 11 meshing with the pinion 5 so that in the movement of one of the jaws motion will be imparted to the other jaw. Thus, the jaws 65 are spaced apart, at all times, equal distances from the center punch 7.

From the foregoing description taken in connection with the accompanying drawing, the construction, mode of operation and 70 manner of employing my invention will be readily apparent. When it is desired to ascertain the center of a cylindrical object, the jaws 8, 8 are moved to the outer extremities of the body 1 and the device applied to the object. The jaws are now 75 moved inwardly along the body 1 and contact with the object at diametrically opposite points, the V-shaped notches 9 adapting the gage to the cylindrical object. The center punch 7 is now struck a sharp blow by a hammer or other implement and punches a hole in the adjacent portion of the object. Thus, the exact center of the object is 80 found. On the other hand, should it be 85 desired to find the center line of a rectangular strip or body of material, the straight edges 10 of the jaws contact with the opposite longitudinal edges of such strip and the center punch is struck to indicate the 90 center line of such strip, while by holding the center punch in engagement with the strip and moving the gage along the length of such strip, a longitudinal central line may be marked upon the rectangular body. 95 To find the center of a square object, the V-shaped notches of the jaws may be engaged with the diagonally opposite corners of such object and the center punch struck a blow, as will be readily understood.

I claim:

A center gage comprising a rectangular body having longitudinally extending grooves formed in the opposite longitudinal edges thereof and an aperture in the central 105 portion thereof opening into said grooves at diametrically opposite points, a hollow shank disposed within said aperture, a pinion loosely surrounding said shank within the aperture and having the teeth thereof 110 working through the bottom walls of said grooves within the latter, a center punch

2
carried by said shank, jaws slidably disposed upon said body at the opposite sides of said center punch, and racks carried by said jaws and disposed within said grooves and
5 engaging the teeth of said pinion whereby the jaws will be spaced equal distances apart from the center punch.

In testimony whereof I affix my signature in presence of two witnesses.

JOHN M. TORMEY.
